CLAIM

The ornamental design for an “inflatable mattress,” as shown and described.

DESCRIPTION

FIG. 1 is a perspective view of an inflatable mattress, according to the principles of the present disclosure.

FIG. 2 is a plan elevation view of the embodiment of FIG. 1.

FIG. 3 is a side elevation view of the embodiment of FIG. 1, the other side view being a mirror image thereof.

FIG. 4 is a top end view of the embodiment of FIG. 1.

FIG. 5 is a bottom end view of the embodiment of FIG. 1; and,

FIG. 6 is a plan view showing the underside of FIG. 1.

The design is composed of two portions, a body portion and a head support and lens portion insertable in an upper central opening of the body portion. The lens is visible in FIG. 6.
